CLAIM

The ornamental design for a lavatory, as shown and described.

DESCRIPTION

FIG. 1 is a top plan view of a lavatory showing my new design;

FIG. 2 is a rear elevational view thereof;

FIG. 3 is a front elevational view thereof;

FIG. 4 is a left side elevational view thereof;

FIG. 5 is a right side elevational view thereof; and

FIG. 6 is a cross-sectional view taken on line 6—6 of FIG. 1.

*Fig. 1**Fig. 2**Fig. 3**Fig. 4**Fig. 5**Fig. 6*
